UNITED STATES PATENT OFFICE.

ERNON V. OLIVER, OF PORTLAND, OREGON.

WATER STILL.

Application filed May 10, 1920, Serial No. 380,216. Renewed October 6, 1924.

This invention relates to a water still.

An object of the invention is to provide an apparatus of the class mentioned so constructed as to afford an unusually large condensing area, whereby the capacity of the apparatus as a water still is especially large.

A further object of the invention is the provision of a unique type of condenser with which either running water or still water under pressure may be used, welling up from the depths of the condenser whereby a constantly cool body of water is maintained in contact with the condenser walls.

The invention has as another object the provision of means for automatically feeding water from the condensing chamber into the distilling chamber, whereby the water within the distilling chamber is always maintained at a proper level.

20 In the drawings:

Figure 1 is a view in perspective of the apparatus, with a fragment broken out of one side to show the details of the interior construction.

25 Figure 2 is a vertical section taken longitudinally,

Figure 3 is a transverse section on the line 3—3 of Figure 2, and

30 Figure 4 is a perspective view similar to Figure 1, but with the cover removed.

The invention, as herein shown, comprises a substantially rectangular receptacle A having the bottom 1, end walls 2 and 3, and the sides 4 and 5. The upper edges of the 35 ends 2 and 3 and the side walls 4 and 5 are beaded as shown at 6.

Near the bottom of the end walls 2 and 3 and side walls 4 and 5 and sloping toward the end wall 2 is located a trough 7 which 40 has an exterior flange 8 secured to the walls of the receptacle A by welding or the like and an interior flange 9 which forms the boundary of a central rectangular opening for a perforate or grated member 11 having supporting legs 10 and which is adapted to 45 support jars or the like containing preserves when the device is being used as a steam cooker. Extending from wall 4 to wall 5 and spaced above the flange 9 of the trough

7, are two rods 12 hinged at one end as at 12' and resting in cups 12^a at the other end and which constitute supports for a grate-like or perforate member 13 which likewise may be used for supporting preserve jars or the like in using the receptacle A as a steam cooker. A condenser B having the shell 14 carries the peripheral flange 15 having the downwardly extending rim 16 beaded as shown at 17, and which fits over the exterior of the receptacle A and fits over the bead 6, thus forming a tight joint while at the same time permitting the condenser B to be easily removed. A flange 18 is also provided at the top of the condenser body B extending along each end thereof from side to side. 65 The bottom of the condenser body or shell B comprises converging end walls 19 and 20 and side walls 21 meeting in the ridge 22, and thus providing a surface of large area on the bottom of the condenser and against 70 which the steam rising from the area bounded by the flange 9 is directed. The edges 23 of the condenser are positioned over the trough 7 so that distilled or condensed water accumulating on the walls 19, 20, and 21 will run toward the edges 23 and be precipitated in the trough 7. Within the bottom of the condenser B and lying in the V-shaped passage formed by the peculiar configuration of the bottom is a pipe 24 which 75 is perforated throughout its length and has an end piece 25 provided with a reduced portion 26 spaced from the wall of the condenser B for the attachment of a suitable pipe for conveying water to the condenser. The end 80 of the pipe 24 may be closed simply by a removable means such as a plug or the like so as to afford easy access to the interior of the pipe for cleaning.

An outlet valve 27 is provided adjacent 85 the top of the condenser B and may be closed by a suitable screw cap 28 if desired. A similar valve 29 closed by a similar cap 30 is secured to the receptacle A at a point approximate the lowest level of the trough 90 7. The top of the condenser B is closed by a cover C which has the upstanding portion 31 carrying handles 32 at each end thereof

2
and having the depending flange 33 which fits down over the flange 18 and has a semi-circular recess indicated by the numeral 33' for the outlet valve 27 so that such cover C for the outlet valve 27 so that such cover C 5 may be fitted onto the still for shipment, or may fit over the bead 6 of the receptacle A, thus forming a cover for either the condenser B or the receptacle A, but in using the device as a still the cover C is never applied 10 as it is desired to utilize the cooling influence of the atmosphere.

The cover C is provided with a lead or other suitable lining 31 to add weight in order to maintain contact of the cover flange 15 when the device is used as a steam cooker, also a hole 31^a is provided as a steam escape and affording passage for the valve spindle to be later described. A water regulating valve for the distilling compartment is indicated at D and consists of a tube 34 fastened at 35 by welding or the like in the apex of the walls 21. This tube is formed with openings 36 beneath the ridge 22 and with openings 37 adjacent the top. Fitting 20 over this tube D at its upper end is a cap 38 having openings 39 for registration with the openings 37 in the tube 34. This cap is held in place by a pin 40 engaging in a groove or slot 41. Within the tube 34 and 25 above the ridge 22 is located a tubular valve seat 42 which has a concave upper end 43 and a tapered passage 44 which receives a tapered valve body 45 carried by a shank 46 connected with a float 47 resting at the water level within the receptacle A. A pin 48 extends from the upper end of the valve body 45 and projects through the cap 38 for guiding the valve. The operation of the valve is as follows. Water flows into the 30 valve tube 34 through the openings 37 and is trapped above the valve seat 42 when the valve body 34 is raised to the closed position by the rise of the float 47. However, on the downward movement of the float 47 the 35 valve body moves away from the sleeve 42 with the result that water from the condenser D flows past the valve body and through the tube 34 and the outlets 36 and into the lower portion of the receptacle A. It will be seen that the rate of flow may 40 be regulated by turning the cap 38 to only partly or wholly uncover the openings 37 in the tube 34.

It will be observed that the condenser D 45 may be entirely removed in order to use the receptacle A as a steam cooker and in the case of such use the cap or cover C may be fitted down over the bead 6 to provide a tight closure. In the case of such use the valve body 45 and the float 47 are also removed.

In constructing this device the component parts thereof are preferably formed of some light material such as aluminum in order to 50 make the device as light as possible for its

size, although it is evident that it may be equally well formed of any other material suitable for the purpose.

I claim:

1. In apparatus of the class described, a receptacle, the lower portion of the interior of which constitutes a well for a liquid to be distilled, a trough within the receptacle extending about the walls thereof and spaced above the bottom of the well, the trough defining a space through which the vapors may rise from the well, a hollow condenser within the upper portion of the receptacle spaced bodily above the plane of the trough and having its condensing surfaces arranged to deliver the distillate to the trough, means for supplying water to the lower portion of the interior of the condenser, a tube extending upwardly within the condenser with its lower discharge end positioned above said space defined by the trough, the said tube having an inlet opening at its upper portion to provide for passage of water from the upper portion of the interior of the condenser through the tube and into the well 90 of the receptacle, and means for regulating the flow of water into said tube, the said means comprising a cap rotatably fitted onto the upper end of the tube and having an opening for registration or partial registration with the opening in the tube in accordance with adjustment of the cap.

2. In apparatus of the class described, a receptacle, the lower portion of the interior of which constitutes a well for a liquid to be distilled, a trough within the receptacle extending about the walls thereof and spaced above the bottom of the well, the trough defining a space through which the vapors may rise from the well, a hollow condenser within the upper portion of the receptacle, and having a bottom comprising side and end walls inclining upwardly into the interior of the condenser, the side and end walls of the body of the condenser being located in upwardly and outwardly inclined planes, the said bottom of the condenser along the line of juncture of the corresponding end and side walls of its body and bottom overlying the said trough where- 115 by liquid condensed upon the outer surfaces of said walls will be delivered into the trough, an overflow from the condenser, and means for supplying a cooling liquid to the condenser comprising a pipe extending around the bottom of the condenser in the angle between the walls of said bottom and the walls of the body of the condenser and having discharge openings presented upwardly and inwardly in the general direction of the adjacent walls of the said bottom of the condenser, and an intake branch in communication with the pipe through which a cooling fluid may be supplied to the 125 said pipe.

3. In apparatus of the class described, a shell having a well in its bottom, means within the shell to receive water of condensation, a condenser tank within the shell having its condensing surfaces arranged to deliver water of condensation to the receiving means, and a perforated water supply pipe leading into the said condenser tank and extending around the interior of the same at the lower portion thereof, the said tank having an upwardly projecting bottom providing an additional condensing surface and surrounded by said pipe.

In testimony whereof I affix my signature.

ERNON V. OLIVER. [L.S.]
